UNITED STATES PATENT OFFICE.

ARTHUR Q. HEINES, OF EVANSVILLE, INDIANA, ASSIGNOR TO SUNBEAM ELECTRIC MANUFACTURING COMPANY, OF EVANSVILLE, INDIANA, A CORPORATION OF INDIANA.

HEADLIGHT.

Application filed April 28, 1922. Serial No. 557,066.

To all whom it may concern:

Be it known that I, ARTHUR Q. HEINES, a citizen of the United States, residing at Evansville, in the county of Vanderburg and 5 State of Indiana, have invented new and useful Improvements in Headlights, of which the following is a full, clear, concise, and exact description, reference being had to the accompanying drawing; forming a part 10 of this specification.

My invention relates to headlights, and it has particular relation to headlights wherein the reflector is closed by an air-tight front glass.

15 More particularly my invention relates to means for securing the reflector, the front glass, and a frame together in such manner that an air-tight aggregate is eventuated. In this connection I provide means whereby the 20 reflector and the glass may be seated in a frame in a markedly expeditious manner and still retain the interior of the reflector free of deteriorating gases or air.

While my improved fastening or securing 25 devices may be utilized in other connections, I will hereinafter describe the same particularly in connection with an improved headlight structure which is described and claimed more specifically in a co-pending application of Lee B. Jones, Serial No. 515,456, 30 assigned to the Sunbeam Electric Manufacturing Co. In this latter application, the benefits and advantages which may be derived from making the interior of the reflector air-tight are set forth; and it is pointed out that the reflector is seated against the front glass of the headlight, the glass in turn being secured in a frame and this latter corresponding to the front door frame of a 35 headlight, but being so removable from the headlight casing that the air-tight aggregate as a whole may be handled in a very simple manner.

My improvement over the disclosure in 40 the above-mentioned application comprises providing means for securing the reflector, glass and frame together by the use of a plurality of manually operated spring members. It is an object of my invention to 45 eliminate entirely the necessity of using a screw driver or wrench to effect the replacement of a broken glass or to obtain access to the interior of a reflector in order to 50 repolish the same or make repairs therewithin.

In this connection, it may be pointed out 55 that repairs in apparatus of this character must frequently be made either on the road or at terminals under such service conditions as to render it highly necessary that such changes may be made by one man and in the 60 shortest possible time. Obviously, therefore, an improvement which contemplates the elimination of the use of screw drivers and wrenches in removing the reflector and its associated front glass from the frame 65 possesses marked advantages.

Again, securing screws or bolts are liable to, and frequently do, work loose unless the replacement work is very carefully performed by the repair man. By utilizing my 70 improved method of securing the assembly the same is maintained in a much more secure manner, and a satisfactory job is ensured irrespective of the care taken by the repair man.

75 A better understanding of my invention may be had from a consideration of the hereinafter description of a device embodying the same taken in connection with the accompanying drawing; in which—

80 Figure 1 is an elevational sectional view of so much of a headlight as is necessary to disclose an operative embodiment of my invention;

Fig. 2 is an enlarged elevational sectional 85 view of the headlight shown in Fig. 1 with the middle portion of the same being broken away to permit of the enlargement; and,

Fig. 3 is an exploded detail view of the 90 particular fastening device which is embodied in my invention.

Referring now more particularly to the drawings, a headlight comprises a main casing 10, having mounted thereon through the medium of a suspension pin 11, a front frame 12. The advantages of such mounting, as well as the manner in which the same secures the air-tight aggregate in position, is more specifically described in the above-described co-pending application.

95 As set forth in that application, the front frame 12 is removable in such manner that the entire air-tight aggregate may by withdrawal be separated from the front of the casing. Secured to the frame is a reflector 13 through the rear of which a light bulb 14 is passed, a particular ring structure 15 being utilized whereby said light may be with-

drawn through the back of the reflector without the necessity of disassembling the frame, glass, and reflector aggregate. Seated between the reflector 13 and the frame 12 is a front glass 16, a gasket 17 being associated with the edge of the glass in such manner as to promote the air-tight fit between the glass and the reflector 13. Mounted on the interior of the frame 12 are brackets 18, the latter being provided with a portion 19 which is turned back on itself to provide an eye. This bracket may be made somewhat resilient if desired.

Pivotedly mounted on the bracket 18 is a link 20 comprising two side plates 21 joined by pins 22 and 23, the pin 22 being surrounded by the bent portion 19 to provide for the pivotal mounting just described. By reason of this mounting it will be observed that the link may be swung through substantially 180 degrees to effect operative and securing relation of the same with respect to the reflector. Mounted on the other pin 23 is a sinuously formed spring member 24 having an engaging portion 25 at its free end which operates to secure the reflector against the rubber gasket 17 and thus keep the interior of the reflector in air-tight condition.

Because there may be certain irregularities in the contour of the reflector at the points where the securing members 25 contact therewith, I further provide a rather soft iron reflector-retaining ring 26, which surrounds the reflector at substantially its greatest diameter and so presses into the arc thereof at this point that such irregularities are compensated for and the tightness of the seal is promoted.

From the above description of my improved fastening means, the operation of the same will be more or less apparent to those skilled in the art. With the parts in the position shown in Fig. 1, and desiring to quickly and without undue effort remove or dismantle the air-tight aggregate, it is only necessary to swing back the link 20 and thus disengage the spring securing means 24 from their securing relation. On the other hand, when it is desired to again build up the aggregate, the reflector glass and frame are placed together and the reflector is then pressed against the glass and frame by moving the links into their inner position about their pivotal mounting. In this connection, it should be observed that the particular formation of my fastening devices and the relatively large freedom of movement of the links are conducive to a very advantageous structure. The resiliency of the spring members 24 contributes largely to this advantage, the breaking of the toggle immediately releases the fastening. When the link is pushed home, however, a very sturdy structure is eventuated. I find that the use of such structure cuts down the time neces-

sary to repair one of these headlights quite considerably, a feature which is of advantage when repairs must be made, as above indicated, under service conditions at terminals, when the time element is all important.

While I have described but one form of my improved fastening device, it is obvious that those skilled in the art may utilize the same in many different ways without departing from the spirit of my invention, and I desire therefore that said invention be broadly interpreted and limited only by the showing of the prior art and the scope of the appended claims.

What I claim as new and desire to secure by Letters Patent of the United States is:—

1. In a headlight, a reflector, a glass or the like extending over said reflector, a frame, and means for quickly detachably securing said glass, a reflector and frame together comprising resiliently mounted and pivotally movable links, and spring securing elements so mounted on said links that said spring elements can be freely rotated to secure said reflector in said frame.

2. In a headlight, a reflector, a glass or the like extending over said reflector, a frame, and means for quickly detachably securing said glass, reflector and frame together comprising resilient brackets secured to said frame, movable links pivotally mounted on said brackets, and reflector retaining springs mounted on said links and adapted to be moved into securing position by the movement of said links.

3. In a headlight, a reflector, a glass or the like extending over said reflector, a frame, and means for quickly detachably securing said glass, reflector and frame together comprising brackets secured to said frame, movable link pivotally mounted on said brackets, reflector retaining springs mounted on one end of said links and adapted to be moved into securing position by the movement of said links, and a retaining ring interposed between said springs and said reflector to compensate for irregularities in the latter.

4. In a headlight, a reflector, a glass or the like extending over said reflector, a frame, and means for quickly detachably securing said glass, reflector and frame together comprising brackets secured to said frame, movable links comprising pairs of plates connected through two pins pivotally mounted by the engagement of said brackets with one pin, and reflector retaining members comprising sinuous spring members mounted movably on the other pin of said links and adapted to be moved into reflector retaining relation upon the movement of said links about their pivotal point.

5. In a headlight, a reflector, a glass or the like extending over said reflector, a

frame, and means for quickly detachably securing said glass, reflector and frame together comprising brackets secured to said frame, movable links comprising pairs of plates connected through two pins pivotally mounted by the engagement of said brackets with one pin, reflector retaining members comprising sinuous spring members mounted movably on the other pin of said links

and adapted to be moved into reflector retaining relation upon the movement of said links about their pivotal point, and a soft iron ring loosely surrounding said reflector and being engaged by said spring members to hold said reflector in desired position. 10

In witness whereof, I have hereunto subscribed my name.

ARTHUR Q. HEINES.

Certificate of Correction.

It is hereby certified that in Letters Patent No. 1,582,138, granted April 27, 1926, upon the application of Arthur Q. Heimes, of Evansville, Indiana, for an improvement in "Headlights," errors appear in the printed specification requiring correction as follows: Page 2, line 5, before the word "glass" insert the words *or goggle*; same page, line 107, claim 3, for the word "link" read *links*; line 121, claim 4, for the word "through" read *by*, and line 122, for the word "by" read *through*; page 3, line 5, claim 5, for the word "through" read *by*, and line 6, for the word "by" read *through*; and that the said Letters Patent should be read with these corrections therein that the same may conform to the record of the case in the Patent Office.

Signed and sealed this 22d day of June, A. D. 1926.

[SEAL.]

M. J. MOORE,
Acting Commissioner of Patents.
